UNITED STATES PATENT OFFICE.

CLINTON A. JOHNSON, OF CHICAGO, ILLINOIS, ASSIGNOR TO JOHNSON COMPOUND GAS ENGINE CO., OF CHICAGO, ILLINOIS, A CORPORATION OF ILLINOIS.

EXPLOSIVE-ENGINE.

1,150,200.

Specification of Letters Patent. Patented Aug. 17, 1915.

Application filed September 19, 1913. Serial No. 790,606.

To all whom it may concern:

Be it known that I, CLINTON A. JOHNSON, a resident of Chicago, in the county of Cook and State of Illinois, have invented certain new and useful Improvements in Explosive-Engines, of which the following is a full, clear, and exact description.

The invention relates to explosive engines and more particularly to improved fluid-operated starting devices therefor.

The invention designs to provide improved starting means which is adapted to start the engine by fluid supplied to the non-working side of the piston.

15 The invention also designs to provide a starting device which is particularly adapted to that type of four cycle engine in which the exhaust from the working side of the piston is conducted to the non-working side 20 to prevent back pressure of the latter side during the compression and exhaust strokes. This object is attained by utilizing the valve for controlling the passage of exhaust fluid to and from the non-working side of the 25 piston to control the flow of compressed fluid, usually air, to operate the piston during the compression and exhaust strokes until the engine has been started and is being operated by ignition of the combustible 30 fluid supply to the working side of the piston.

The invention further designs to provide improved starting means for explosive engines.

35 The invention consists in the several novel features hereinafter set forth and more particularly defined by claims at the conclusion hereof.

In the drawings, Figure 1 is a vertical 40 section of an explosive engine embodying the invention. Fig. 2 is a section taken on line 2—2 of Fig. 1. Fig. 3 is a section taken through the intake valve for combustible. Fig. 4 is a horizontal section taken on line 45 4—4 of Fig. 1.

The improved explosive engine is of the four cycle type and is shown as applied to a single cylinder engine, but it will be understood that it may be applied to multi-cylinder engines, if desired. Cylinder 12 is provided with a water jacket 13. A shaft 14 is journaled in bearings 15 on a base or bracket 16 to which is secured the lower end of the cylinder, and is formed with a crank 17. 55 A piston 18 is slidable in the cylinder and

is connected to the crank by a pitman 19 which is pivoted, as at 20, to the piston, and as at 21 to crank 17. A spark-plug 22, which may be operated by any suitable means, as well understood in the art, serves 60 to ignite at the proper time the combustible charge in the combustion-chamber 12' of the cylinder above the piston. A lubricator 27 connected to the cylinder 12 supplies lubricant to the piston. 65

A supply port 24 is formed in the cylinder casing through which the combustible fluid is supplied to the chamber 12'. A check valve 25, which is normally closed by a spring 26, serves to close the supply-port 70 at all times except during the intake stroke of the piston. Port 24 is supplied with fluid through a pipe 24' which is connected thereto. Pipe 24' may be connected to a carburetor of usual construction, as well understood in the art. 75

An exhaust port 28 is formed in the cylinder-casing and a valve 30, secured to a stem 31, controls the exhaust from the combustion chamber 12' on the working side of the 80 piston. This valve is normally closed by a spring 32 and is opened during the exhaust stroke of the piston by a cam 32' on a shaft 33 which is journaled in suitable bearings in bracket 16 and is driven by crank-shaft 14 85 by means of a pinion 35 rotating with the crank-shaft and a gear 36 on cam-shaft 33. Cam 32' is adapted to engage a roller 37 mounted in the lower end of rod 40 which is slidably held in a guide 39. Rod 38 is adjustably connected to the lower end of valve-rod 31 by a lug 41 and nuts 42 which engage a screw thread on the upper end of rod 40. This mechanism for operating the exhaust valve 30 permits the exploded charge to exhaust 90 from the combustion chamber on the working side of the piston during the fourth stroke of the piston. 95

In practice, it has been found that the unequal pressures upon the non-working and 100 working sides of the piston during the exhaust stroke retard the operation of the engine and lessen the power developed thereby. For the purpose of overcoming this loss of power, provision is made for transferring the exploded charge from the working side of the piston to the non-working to 105 equalize the pressures upon its sides, and which means effects direct transference so that the pressure will not be reduced when trans- 110

ferred to the non-working side of the piston. Exhaust port 28 is connected by a pipe 45 to a duct 46 formed in the top 47 of bracket 16 which is fitted to that end of the cylinder 12 through which pitman 19 passes. This top 47 is also formed with a duct 48 for discharging the fluid in the cylinder chamber 12^a on the non-working side of the piston, to atmosphere. The inlet to, and outlet from, said chamber 12^a through ducts 46 and 48, respectively, are controlled by a slide valve 50 which is fitted in a way 51 formed in the lower end or head 12^c of the cylinder-casing and slides upon the top 47. 15 A wear ring 52 is held in top 47 around duct 46 to prevent the passage of fluid through ducts 46 when the slide valve 50 is closed. A packing-ring 53 in ring 52 prevents leakage between ring 52 and the top 47 in which 20 ring 52 is held by a bolt 52'. Bolt 52' permits a slight vertical play of ring 52 so that pressure against the underside of said ring will cause a snug fit between the valve and ring. Any wear of the ring will not permit 25 any leakage because the ring will be seated against the underside of valve 50 by any pressure in duct 46.

Slide valve 50 is operated to alternately open duct 46 to admit fluid under pressure 30 expelled from the combustion chamber 12' by piston 18, to chamber 12^a on the non-working side of the piston, and to open duct 48 for the discharge of fluid from the said chamber by a suitable connection with pitman 19, the oscillation of the pitman being utilized for this purpose. This operating connection between the pitman and the valve 50 comprises a ball-sleeve 54 which is held in a ball-shaped socket formed in valve 50 and a bearing plate 55 secured to the top thereof by bolts 55'. Pitman 19 extends and slides through sleeve 54 and a packing-box 56 on the sleeve prevents leakage between the sleeve and the pitman. By means of this 40 connection, the lateral or swinging movement of the pitman is utilized to operate the valve for controlling the flow of fluid to and from the non-working side of the piston. The sliding connection between sleeve 54 and the pitman permit the latter to move longitudinally. Resultantly, when the piston is at the end of its power-stroke, exhaust valve 30 will be opened for the escape of fluid from the working side of the piston to the 45 exhaust duct 28, pipe 45 and duct 46. During the commencement of the exhaust-stroke, valve 50 will uncover duct 46 to permit the fluid to pass to chamber 12^a on the non-working side of the piston. At such time, valve 50 will keep exhaust duct 48 closed. Thus, during the exhaust stroke, the exploded charge will be transferred to the non-working side of the piston, equalize the pressures upon its sides, and overcome any back-pressure upon the non-working side of

the piston during the exhaust-stroke. At the end of the exhaust-stroke of piston 18, valve 50 will close port 46 and uncover exhaust-port 48 to permit fluid to escape from the non-working side of the piston during 70 the intake stroke, and to permit the products of combustion to finally escape.

During the compression-stroke, exhaust port 48 will be closed, and the exhaust valve 30 will be also closed. To prevent back-pressure or a vacuum on the non-working side of the piston and to save the power required from sucking the air into the cylinder during this stroke, an expansion chamber and inlet, which will be operative during this 80 stroke, are provided. A cylinder 60 is secured to the upper end of a pipe section 61 which is secured in a fitting 62 which has a passage connecting with the exhaust-port 28. A piston 63 is slidably fitted in this 85 cylinder. Inlet ports 64 are formed in said piston and are normally closed by a check-valve 65 which is slidably mounted in said piston and is held normally closed by spring 66. The top 67 of cylinder 60 has ports 68 90 to admit air to the top of the cylinder. During the exhaust stroke, the pressure of the products of combustion will at times exert sufficient pressure upon the underside of piston 63 to cause it to rise in cylinder 60, 95 and this fluid is utilized to prevent back pressure upon the non-working side of the piston during the compression-stroke of piston 18. During the compression-stroke, the contents of cylinder 60 pass through 100 duct 46, which is uncovered at that time, and prevent formation of a vacuum in chamber 12^a on the non-working side of the engine-piston. The fluid in the exhaust pipe 45 and expansion cylinder 60 is usually insufficient 105 for this purpose and to supply the deficiency, air will be admitted through ports 64 in piston 63 when piston 63 has been drawn downward to the lower end of cylinder 60. In this manner, the piston will not encounter 110 material resistance from the lack of fluid-pressure upon the non-working side during the compression-stroke.

A valve *a* in a pipe *a'*, which is connected to a source of supply of fluid, such as air under pressure, and to pipe 45, controls the supply of fluid to the non-working side of the cylinder for starting the engine. A check-valve *b* is provided in pipe 45, is pivoted therein, as at *b'*, and is provided with a weighted arm *b*² on the outside of said pipe. This check-valve prevents compressed air from passing into the exhaust-passage 28. This check-valve permits exhaust fluid to pass freely to duct 46 during normal running of the engine, and will be held closed by fluid pressure from valve *a* in starting the engine.

Slide valve 50, besides controlling the passage of exhaust-fluid to and from the 130

non-working side of the piston, serves, when check-valve *b* is closed, to uncover duct 46 during the instrokes of piston 18 and to uncover exhaust port 48 during the outstrokes 5 of the piston, so that during each instroke, the non-working side of the piston will be exposed to air under pressure and be operated thereby until the engine has been started. In multi-cylinder engines, the 10 cranks on the crank-shaft are usually set in such relative position that successive inward operation of the pistons will suffice to operate the crank-shaft a complete revolution, the air supply pipe *a'* being connected to all 15 of the exhaust pipes 45 in the same manner, or by a manifold between valve *a* and pipes 45. In a single cylinder engine, the rapid operation of the piston during the compression and exhaust strokes thereof usually 20 suffices, with the force of the usual fly-wheel, to operate the crank-shaft complete revolutions.

The starting operation of the improved engine will be as follows: During the intake 25 and power strokes of the piston 18, slide valve 50 will cover duct 46 and prevent compressed fluid from passing to the non-work- 30 ing side of the cylinder. In multi-cylinder engines, the cranks of the crank-shaft are usually set in such relation that one or more 35 of the pistons will always be on either the compression or exhaust stroke, and during these strokes, one or more of the ports 46 will be uncovered to admit fluid under pres- 40 sure from pipe *a'* when valve *a* is opened, so that the non-working side of each piston, during the compression and exhaust strokes will be exposed to compressed air and be operated thereby to drive the crank-shaft.

45 When the pressure in the exhaust-passage 28 preponderates, after the engine commences to be operated by combustible fluid on the working side of the piston, it will force open valve *b* to permit the exhaust to escape through duct 46 to the non-working side of the cylinder and then valve *a* will be closed. The operation of the engine after it has been started will be as follows: Assuming piston 18 to be at the upper end of cylinder 12, it 50 will, during its outward movement, open check valve 25 and draw a charge of combustible fluid through supply port 24 into the combustion-chamber 12'. During this stroke of the piston, slide-valve 50 will uncover exhaust port 48 to permit fluid in chamber 12^a on the non-working side of the piston to escape through said duct. During the next in-stroke of piston 18, the charge 55 of combustible fluid in chamber 12' will be compressed, intake valve 25 and exhaust valve 30 being closed. During this compression-stroke of piston 18, pitman 19 will uncover duct 46 and permit fluid in exhaust pipe 45 and expansion-cylinder 60 to pass to chamber 12^a on the non-working side of the

engine-piston and, if there is a deficiency of fluid, air will be drawn through ports 64 in piston 63. At the end of the compression-stroke, spark-plug 22 will be operated to ignite the compressed charge in chamber 12' 70 to drive the piston 18 outwardly. During the power-stroke, pitman 19 will operate slide-valve 50 to permit fluid in chamber 12^a to escape through duct 48. During the succeeding in-stroke, exhaust-valve 30 will 75 be opened by cam 32 and the exploded charge or fluid will pass from chamber 12' through exhaust-duct 24, pipe 45 and duct 46 to the chamber 12^a on the non-working side of the piston. During the exhaust- 80 stroke, pitman 19 will operate slide-valve 50 to uncover port 46 for transferal of fluid from the working side to the non-working side of the piston and thus equalize the pressure in the sides of the piston. In many 85 cases, this fluid is under pressure and any excess of pressure will cause this fluid to lift piston 63 in expansion-cylinder 60 and, during the succeeding compression-stroke of piston 18, will exhaust the fluid from cylinder 60 and draw piston 63 downwardly 90 in cylinder 60.

The invention thus exemplifies an improved engine which may be started by supplying compressed fluid to the non-working 95 side of the cylinder under control of a valve at the non-working end of the cylinder and which is operated by a pitman; also one which exemplifies the use of the valve which controls the supply of exhaust to the 100 working side of the cylinder, to control the flow of compressed fluid in starting the engine.

The invention is not to be restricted to the details set forth, since these may be modified 105 within the scope of the appended claims, without departing from the spirit and scope of the invention.

Having thus described the invention, what I claim as new and desire to secure 110 by Letters Patent, is:

1. In an explosive engine, the combination with a piston, a crank, a pitman connecting the piston and crank, a casing having a cylinder therein extending from both sides of the piston, ignition means, and means for supplying combustible fluid to the cylinder at one side of the piston for operating it, of means for supplying fluid under pressure to the non-working side of the piston to start the engine, and a valve operated by the pitman for controlling the passage of fluid to the non-working side of the piston.

2. In an explosive engine, the combination with a piston, a crank, a pitman connecting the piston and crank, a casing having a cylinder therein extending from both sides of the piston, ignition means, and means for supplying combustible fluid to 125

the cylinder at one side of the piston for operating it, of means for supplying fluid under pressure to the non-working side of the piston to start the engine, and a valve operated by the pitman for controlling the passage of fluid to and from the non-working side of the piston.

3. In an explosive engine, the combination with a piston, a crank, a pitman connecting the piston and crank, a casing having a cylinder therein extending from both sides of the piston, ignition-means, and means for supplying combustible fluid to the cylinder at one side of the piston for operating it, of means for supplying fluid under pressure to the non-working side of the piston, to start the engine, and a valve at one end of the cylinder operated by the pitman for controlling the passage of fluid to and from the non-working side of the piston.

4. In an explosive engine, the combination with a piston, a crank, a pitman connecting the piston and crank, a casing having a cylinder therein extending from both sides of the piston, ignition means, means for supplying combustible fluid to the cylinder at one side of the piston for operating it, a slide valve at one end of the cylinder operated by the pitman, for controlling the passage of fluid to the non-working side of the piston, and means for supplying fluid under pressure to said valve and to the non-working side of the piston to start the engine.

5. In an explosive engine, the combination with a piston, a crank, a pitman connecting the piston and crank, a casing having a cylinder therein extending from both sides of the piston, ignition-means, means for supplying combustible fluid to the cylinder at one side of the piston for operating it, means for conducting the exhaust from the working side of the piston to its non-working side, and a pitman-operated valve for controlling the passage of the exhaust to the non-working side of the cylinder, of means for supplying fluid under pressure to said conducting means to start the engine.

6. In an explosive engine, the combination with a piston, a crank, a pitman connecting the piston and crank, a casing having a cylinder therein extending from both sides of the piston, ignition means, means for supplying combustible fluid to the cylinder at one side of the piston for operating it, means for conducting the exhaust from the working side of the piston to its non-working side, and a pitman-operated valve for controlling the passage of the exhaust to the non-working side of the cylinder, of means for supplying fluid under pressure to said conducting means to start the engine, and means for preventing the starting fluid

from passing back through said conducting means.

7. In an explosive engine, the combination with a piston, a crank, a pitman connecting the piston and crank, a casing having a cylinder therein, extending from both sides of the piston, ignition-means, means for supplying combustible fluid to the cylinder at one side of the piston for operating it, means for conducting the exhaust from the working side of the piston to its non-working side, intake and exhaust valves, and a pitman-operated slide valve at one end of the cylinder for controlling the passage of the exhaust to the non-working side of the cylinder, of means for supplying fluid under pressure to said slide-valve to start the engine.

8. In an explosive engine, the combination with a piston, a crank, a pitman connecting the piston and crank, a casing having a cylinder therein extending from both sides of the piston, ignition means, means for supplying combustible fluid to the cylinder at one side of the piston for operating it, means for conducting the exhaust from the working side of the piston to its non-working side, and a pitman operated valve for controlling the passage of the exhaust to the non-working side of the cylinder and the exhaust therefrom, of means for conducting fluid under pressure to said valve to start the engine.

9. In an explosive engine, the combination with a piston, a casing having a cylinder therein extending from both sides of the piston, ignition means, means for supplying combustible fluid to the cylinder at one side of the piston for operating it, means for conducting the exhaust from the working side of the piston, to its non-working side, and an engine-operated valve for controlling the passage of the exhaust to the non-working side of the cylinder, of means for supplying fluid under pressure to said conducting-means to start the engine and a check-valve in said conducting-means, for preventing the fluid under pressure from passing to the working side of the cylinder.

10. In an explosive engine, the combination with a piston, a casing having a cylinder therein extending from both sides of the piston, ignition means, means for supplying combustible fluid to the cylinder at one side of the piston for operating it, means for conducting the exhaust from the working side of the piston to its non-working side, and an engine operated valve at one end of the cylinder for controlling the passage of the exhaust to the non-working side of the cylinder and the exhaust therefrom, of means for supplying fluid under pressure to said conducting-means to start the engine, and a check-valve in said conducting-means,

for preventing the fluid under pressure from passing to the working side of the cylinder.

11. In an explosive engine, the combination with a piston, a casing having a cylinder therein extending from both sides of the piston, ignition means, means for supplying combustible fluid to the cylinder at one side of the piston for operating it, means for conducting the exhaust from the working side of the piston to its non-working side, intake and exhaust valves, and an engine-operated valve for controlling the passage of the exhaust to the non-working side of the cylinder, of means for supplying fluid under pressure to said conducting-means to start the engine and a check-valve in said conducting-means for preventing the fluid under pressure from passing to the exhaust valve.

12. In an explosive engine, the combination with a piston, a casing having a cylinder therein extending from both sides of the piston, ignition means, means for supplying combustible fluid to the cylinder at one side of the piston for operating it, an exhaust valve, a pipe for conducting the exhaust from said valve to the non-working side of the piston, and an engine-operated valve for controlling the passage of the exhaust to the non-working side of the cylinder, of means for supplying fluid under pressure to said conducting-means to start the engine, and a check-valve in said pipe for preventing the fluid under pressure from passing to the said exhaust valve.

13. In an explosive engine, the combination of a piston, a casing having a cylinder therein extending from both sides of the piston, ignition means, means for supplying combustible fluid to the cylinder at one side of the piston for operating it, a crank-shaft, a pitman between the crank-shaft and the piston, a valve at one end of the cylinder through which the pitman extends, for controlling the passage of fluid to the non-working side of the cylinder, and means for supplying fluid under pressure to the non-working side under control of said valve, to start the engine.

14. In an explosive engine, the combination of a piston, a casing having a cylinder therein extending from both sides of the piston, ignition means, means for supplying combustible fluid to the cylinder at one side of the piston for operating it, a crank-shaft, a pitman between the crank-shaft and the piston, a valve at one end of the cylinder through which the pitman extends having means for controlling the passage of fluid to the non-working side of the cylinder and the exhaust therefrom, and means for supplying fluid under pressure to the non-working side under control of said valve, to start the engine.

15. In an explosive engine, the combination of a piston, a casing having a cylinder therein extending from both sides of the piston, ignition means, means for supplying combustible fluid to the cylinder at one side of the piston for operating it, a crank-shaft, a pitman between the crank-shaft and the piston, a valve at one end of the cylinder through which the pitman extends for controlling the supply of fluid to the non-working side of the cylinder, means for conducting the exhaust from the working side of the piston to the said valve, and means for supplying fluid under pressure to the non-working side under control of said valve, to start the engine.

16. In an explosive engine, the combination of a piston, a casing having a cylinder therein extending from both sides of the piston, ignition means, means for supplying combustible fluid to the cylinder at one side of the piston for operating it, a crank-shaft, a pitman between the crank-shaft and the piston, a valve at one end of the cylinder through which the pitman extends, having means for controlling the supply of fluid to the non-working side of the cylinder, and the exhaust therefrom, and means for supplying fluid under pressure to said valve, to start the engine, said valve controlling the supply of exhaust and the starting fluid to the non-working side of the piston.

17. In an explosive engine, the combination of a piston, a casing having a cylinder therein extending from both sides of the piston, ignition means, means for supplying combustible fluid to the cylinder at one side of the piston for operating it, a crank-shaft, a pitman between the crank-shaft and the piston, a slide valve at one end of the cylinder through which the pitman extends having means for controlling the supply of fluid to the non-working side of the cylinder and the exhaust therefrom, means for conducting the exhaust from the working side of the piston to said valve, and means for supplying fluid under pressure to said valve, to start the engine.

18. In an explosive engine, the combination of a piston, a casing having a cylinder therein extending from both sides of the piston, ignition means, means for supplying combustible fluid to the cylinder at one side of the piston for operating it, a crank-shaft, a pitman between the crank-shaft and the piston, a slide at one end of the cylinder through which the piston extends, and means for supplying fluid under pressure to the pitman side of the cylinder, to start the engine.

19. In an explosive engine, the combination of a piston, a casing having a cylinder therein extending from both sides of the piston, ignition means, means for supply-

- ing combustible fluid to the cylinder at one side of the piston for operating it, a crank-shaft, a pitman between the crank-shaft and the piston, a slide at one end of the cylinder, through which the pitman extends, a pivotal and sliding connection between the pitman and said slide, and means for supplying fluid under pressure to the pitman side of the piston, to start the engine.
10. 20. In an explosive engine, the combination of a piston, a casing having a cylinder therein extending from both sides of the piston, ignition means, means for supplying combustible fluid to the cylinder at one side 15 of the piston for operating it, a crank-shaft, a pitman between the crank-shaft and the piston, a slide at one end of the cylinder through which the pitman extends, a sleeve mounted on said slide, a pivotal connection 20 between the sleeve and the pitman, and means for supplying fluid under pressure to the pitman side of the cylinder, to start the engine.

21. In an explosive engine, the combination with a piston, a casing having a cylinder therein extending from both sides of the piston, ignition-means, means for supplying combustible fluid to the cylinder at one side of the piston for operating it, a crank-shaft, a pitman between the crank-shaft and the piston, a valve at one end of the cylinder through 25 which the pitman extends for controlling the supply of fluid to the non-working side of the cylinder, a pipe for conducting the exhaust from the working side of the piston to said valve and the non-working side, a pipe for supplying fluid under pressure to said valve, a valve in the latter pipe for controlling the supply of starting fluid to said valve, and a check-valve in the exhaust 30 conducting pipe. 35 40
